UNITED STATES PATENT OFFICE.

ISAAC CENTNER, OF TORONTO, ONTARIO, CANADA.

CAP.

1,092,429.

Specification of Letters Patent.

Patented Apr. 7, 1914.

Application filed March 27, 1913. Serial No. 757,197.

To all whom it may concern:

Be it known that I, ISAAC CENTNER, of the city of Toronto, in the Province of Ontario, Canada, have invented certain new and useful Improvements in Caps, of which the following is a specification.

This invention relates to improvements in cloth caps provided with stiffened peaks and my object is to devise a cap of this kind which can be drawn down firmly on the head without binding disagreeably on the forehead and which will readily adapt itself to several different sizes of head so that fewer sizes of cap need be carried by a retailer to fit his customers.

I attain my object by means of the construction hereinafter described and illustrated in the accompanying drawings in which—

20 Figure 1 is a fore-and-aft section of my improved cap. Fig. 2 a plan view of the under side of the same showing a slight modification in which the front of the sweat band is cut away.

25 In the drawings like numerals of reference indicate corresponding parts in the different figures.

The cap 1 is in general of ordinary construction and is provided with the sweatband 30 2 and the peak 3. The peak is provided with the stiffener 4. In the ordinary cap the rearward arc-shaped edge of the stiffener meets the lower edge of the front of the sweatband. In my cap a crescent-shaped piece is 35 removed from the rearward edge of the stiffener which now follows the heavy dotted line 5. (See Fig. 2.) The top and peak are sewed together along this line leaving the crescent-shaped piece 6 of soft cloth behind 40 the line of stitching. The sweatband is preferably secured at its lower edge to the inner edge of this crescent-shaped piece. This crescent-shaped piece being soft and more or less yielding makes the cap easy to wear 45 and easily stretchable to fit different sized heads.

To give the cap a greater range of ad-

justability I find it preferable to secure a piece of elastic to the inner edge of the crescent-shaped piece 6. This elastic piece 50 7 is preferably independent of the sweat band which latter is formed of bias cut material or is otherwise made stretchable preferably at the front alone. The stitches of the seam between the sweat band, the elastic, 55 and the cloth of the inner edge of the peak pass through several thicknesses of material, which necessarily gives the same considerable elasticity, and this elasticity is readily increased by maintaining only a light tension on the thread while the seam is being sewn.

What I claim as my invention is:

1. In a cap the combination of a cloth top; a cloth covered peak including a 65 stiffener cut to leave an unstiffened stretchable crescent-shaped portion of cloth at the rearward side of the peak; and a stretchable sweat band secured to the inner edge of said crescent shaped portion, the top of the cap 70 being secured to the peak along the outer edge of said unstiffened portion.

2. In a cap the combination of a cloth top; a cloth covered peak including a 75 stiffener cut to leave an unstiffened stretchable crescent-shaped portion at the rearward side of the peak; and a piece of elastic secured along the inner edge of said crescent shaped portion.

3. In a cap the combination of a cloth 80 top; a cloth covered peak including a stiffener cut to leave an unstiffened stretchable crescent-shaped portion at the rearward side of the peak; a piece of elastic secured along the inner edge of said crescent shaped 85 portion; and a stretchable sweatband also secured along the inner edge of said crescent-shaped portion.

Dated at Toronto this 18th day of March 1913.

ISAAC CENTNER.
